UNITED STATES PATENT OFFICE.

RICHARD HOWLAND HUNT, OF PORT CHESTER, NEW YORK.

DESIGN FOR AN EMBLEM.

No. 39,242.

Specification for Design.

Patented April 7, 1908.

Application filed February 25, 1908. Serial No. 417,749. Term of patent 14 years.

To all whom it may concern:

Be it known that I, RICHARD HOWLAND HUNT, of Port Chester, in the county of Westchester, State of New York, have invented a new, original, and ornamental Design for an Emblem, of which the following is a description, reference being had to the accompanying drawing, forming a part hereof.

The figure is a plan view of an emblem showing my design as applied to a metal plate.

There is on the upper part of the plate, the words "Automobile Club of America" and on the body of the plate the representation of

the flag or pennant having its body of yellow with a longitudinal central band of green and a vertical band of the same color. At the intersection of the longitudinal and vertical bands is a conventional representation of a wheel having its hub and spokes of red and its rim of white.

I claim:

The ornamental design for an emblem as shown.

RICHARD HOWLAND HUNT.
